LOAD TRANSFER UNIT

James H. Jacobson, Chicago, Ill.

Application December 29, 1943, Serial No. 516,019

7 Claims. (Cl. 94—17)

1

This invention is directed to a load transfer unit, the sections of which are adapted to be embedded within concrete road slabs which present their faces on opposite sides of a road joint, and thus serve as mountings for a dowel which bridges the gap and serves to transmit load stresses thereover. The sections of the unit are designed to afford a firm and effective anchorage within the concrete without the provision of widely extended wings, fins or other projections which introduce excessive irregularities in the surface contour of the unit sections and which may under varying conditions of stress and resultant vibration act as focal points in the initiation of disintegrating or funneling action.

The special features of the present invention are directed to the provision of a stake or spike depending from the upper portion of the unit in position to be driven into the subgrade and to the further provision of an upwardly extending arm which affords a driving head adapted to receive the blows of a hammer or mallet in driving the stake into position.

Further objects and details will appear from a description of the invention in conjunction with the accompanying drawing wherein,

Figure 1 is a side elevation of the unit installed as a contraction joint;

Fig. 2 is a longitudinal sectional view of the two sections of the unit, temporarily united by an easily frangible bolt for shipment and in condition to be installed as an expansion joint;

Fig. 3 is an inner end elevation of one of the unit sections;

Fig. 4 is an inner end view of the thin metal cap; and

Fig. 5 is an edge view of the lower or stake portion of a modified form of section.

The unit as a whole consists of two sections 10, which are preferably malleable iron castings, and since the two are duplicates, a description of one will suffice for both. The sections stand in opposed relation to one another on opposite sides of the joint gap with their inner ends exposed in flush relation to the face of the concrete slab within which the section is embedded.

Each section is integrally formed to provide a backwardly extending body portion 11, embedded save for its inner face, in the concrete, a vertical standard 12 having its rear face and edges embedded, and a downward extension in the form of a tapered stake 13 adapted to be driven into the subgrade.

The body portion is of reduced circular cross section at its inner end 14 and enlarged circular

2

cross section at its rear end 15, but with the axes of successive cross sections lying in an obliquely downwardly and backwardly extending line, which gives to the body a conoidal formation presenting a horizontal medial profile 16 along its upper surface and an oblique medial profile 17 along its lower medial surface so that the contour of the body as a whole gives it the characteristics of a wedge, progressively enlarging toward its rear end but presenting an upper surface which along its longitudinal center line is normal to downwardly directed pressure lines. Moreover, the contour of the entire upper surface is such as to minimize the wedging tendency to produce longitudinal displacement under vertical stress, while the under surface which is free from vertical stress, is so configured as to increase its anchoring effect.

The under surface of the body being obliquely disposed to the horizontal in substantial degree along its medial profile when embedded, affords substantial resistance to longitudinal displacement while the rear wall surface of the body is planate and without lateral extensions which, if present, might tend, under vibration, to dig into and abrade or wear away the adjacent concrete.

At the forward inner end of the body are two symmetrically disposed laterally projecting fins 18, the forward ends of which lie flush with the inner face of the body while the rear ends taper down and merge into the curved wall surface near the middle on each side.

The body of each unit section is provided from end to end with a bore 19 which runs parallel with the upper medial profile, and the bores of the unit sections are aligned to receive a dowel 20 which is of a length to extend at each end beyond the companion bodies, even when separated to the degree shown in Fig. 1. Each of the bodies at its rear end is shouldered concentrically with the bore to provide a reduced flange 21, and onto one of the flanges so formed, is fitted a cap 22 of thin metal having a cylindrical body 23 of a size to provide a sliding fit around the protruding end of the dowel and of a length slightly greater than the maximum protrusion of the dowel, so as to provide within the concrete of one of the slabs a void or cavity adapted to permit movement of the dowel within said void to allow for expansion and contraction of the concrete due to changes in temperature.

The cap is closed at its rear end 24 and offset at its forward end 25 to closely fit upon the flange 21, and in order to temporarily hold the dowel 55 and the unit section in proper relation to one an-

other, the cap is indented at 26 to provide a fragile abutment for the end of the dowel at a point well in advance of the closed end of the cap.

The opposite end of the dowel projects beyond the end of the body of the companion unit section, so that, when the concrete is poured, it will impinge directly against the exposed end of the dowel and embed the same against movement together with the associated unit section.

Each unit section is carried by its standard 12 which at its upper end has a width substantially equal to the diameter of the forward end of the body, exclusive of the fins 18. The standard is of slightly increasing width toward its lower end where it merges into the downwardly projecting stake 13 which tapers to a blunt point and is of a length sufficient to permit driving into the subgrade to the extent required to bring the body of the unit section to the intended level. If desired the standard at its point of juncture with the stake can be provided with a rearwardly extending foot 27 to gauge the elevation of the body above the subgrade, but the provision of such a foot is optional and it can be omitted in cases where it is desirable to drive units of the same size to different levels to meet local conditions.

In order to facilitate the driving in of the stakes the unit section is provided with an upwardly extending arm 28, the inner face of which lies flush with the standard at the inner end of the body, and terminates at its upper end in a rearwardly extending flange affording a driving head 29 adapted to afford a sufficiently extended flat surface to receive the impact of a hammer or sledge.

In order to unite the sections temporarily in close face contact with one another, an aperture 30 is provided in each section to receive a small fragile headed bolt 31 and nut 32 which will be easily ruptured when the sections are embedded and subjected to the strains caused by the contraction of the concrete and the widening of the gap between the faces of the concrete slabs.

When the unit is to be employed as a contraction joint the parts are adjusted as in Fig. 1, with a wide gap between the opposed faces of the unit sections and the uncapped end of the dowel protruding but slightly from the associated body section. In this case in the event of contraction of the gap, due to expansion of the concrete, the capped end of the dowel will be free to move within the recess afforded within the cap, while the opposite uncapped end of the dowel will move in unison with the unit section through which it is entered. The indentation 26 in the fragile wall of the cap affords merely a temporary obstruction which will be sheared away as the dowel slides toward the end of the cavity afforded by the cap.

When the unit is used as an expansion joint, the faces of the unit sections will initially lie close together on opposite sides of a narrow gap and with the uncapped end of the dowel protruding to a substantial degree. In such case, as the concrete contracts, and the gap increases in width, the bolt 31 will be ruptured and the capped end of the dowel will permit the associated unit section to move along the dowel to the necessary extent.

The provision of the stake in facial alignment with the standard and the upwardly extending headed arm, affords simple and effective means for firmly positioning the unit sections at the required elevation prior to the pouring of the concrete while the alignment of these parts of the structure enables the driving impact to be

properly directed to ensure vertical penetration of the subgrade and aligned spacing of the companion sections of the unit.

The conoidal formation of the body serves to anchor the unit section firmly within the concrete in such a way as to resist any tendency to move forward toward the gap while the flat rear end of the body which is of maximum diameter presents a widely extended surface to resist movement in the opposite direction, so that widely extended anchoring wings or the like are unnecessary.

Moreover, the open ended bores through the two unit sections permit the use of dowels of any desired length since the degree of protrusion of the ends of the dowel from the bodies of the unit sections can be varied to meet diverse conditions. Although I have described a dowel which is formed separately from the respective sections and which when in use is immovably held within one of the sections, it is obvious that the dowel might be permanently united therewith without materially modifying the structure or function of the device as a whole.

Although it is preferred to configure the entire section as an integral casting, it is possible to form the standard with its upper arm and depending stake from flat metal plate and to weld the same to the forward end of the body so that in the claims it will be understood that the units are not necessarily of integral construction unless otherwise indicated.

Where I employ the term "conoidal," I do not intend to limit the claims to a body structure in which the cross diameter at any point is truly circular, since the term is intended to define and include ovate, elliptical or similar forms which involve a departure from true circularity.

I claim:

1. In a load transference device, a unit section consisting of a body having secure to its underside a standard of a length to support the body at the intended elevation above the subgrade and having in line with the standard a depending extension forming a stake adapted to be percussively driven into the subgrade, the body being also provided with an upwardly extending driving arm aligned with the standard and the stake adapted to receive a driving impact, and a dowel carried by the body and extending inwardly beyond the front end thereof.

2. In a load transference device, a unit section consisting of a body of conoidal formation enlarging from the inner front end toward the rear end and having at its inner front end a standard of a length to support the body at the intended elevation above the subgrade and having in line with the standard a depending extension forming a stake adapted to be percussively driven into the subgrade, the body being also provided with an upwardly extending driving arm aligned with the standard and the stake adapted to receive a driving impact, and a dowel carried by the body and extending inwardly beyond the front end thereof.

3. In a load transference device, a unit section consisting of a body having at its inner front end a standard of a length to stand in flush relation to the face of a concrete slab and support the body at the intended elevation above the subgrade and having in line with the standard a depending extension forming a stake adapted to be percussively driven into the subgrade, the body being also provided with an upwardly extending driving arm aligned with the standard and the

stake adapted to receive a driving impact, and a dowel carried by the body and extending inwardly beyond the front end thereof.

4. In a load transference device, a unit section consisting of a body of conoidal formation enlarging from the inner front end toward the rear end and having at its inner front end a standard of a length to stand in flush relation to the face of a concrete slab and support the body at the intended elevation above the subgrade and having in line with the standard a depending extension forming a stake adapted to be percussively driven into the subgrade, the body being also provided with an upwardly extending driving arm aligned with the standard and the stake adapted to receive a driving impact, and a dowel carried by the body and extending inwardly beyond the front end thereof.

5. In a load transference device, a unit section consisting of a body having at its inner front end a standard of a length to stand in flush relation to the face of a concrete slab and support the body at the intended elevation above the subgrade and having in line with the standard a depending extension forming a stake adapted to be percussively driven into the subgrade, the body being also provided with an upwardly extending driving arm aligned with the standard and the stake and provided with an enlarged driving head adapted to receive a driving impact, and a dowel carried by the body and extending inwardly beyond the front end thereof.

6. In a load transference device, a unit section consisting of a body of conoidal formation

enlarging from the inner front end toward the rear end and having at its inner front end a standard of a length to stand in flush relation to the face of a concrete slab and support the body at the intended elevation above the subgrade and having in line with the standard a depending extension forming a stake adapted to be percussively driven into the subgrade, the body being also provided with an upwardly extending driving arm aligned with the standard and the stake and provided with an enlarged driving head adapted to receive a driving impact, and a dowel carried by the body and extending inwardly beyond the front end thereof.

7. In a load transference device, a first unit section consisting of a body having at its front end a standard of a length to stand in flush relation to the face of a concrete slab and support the body at the intended elevation above the subgrade and having in line with the standard a depending extension forming a stake adapted to be percussively driven into the subgrade, the body being also provided with an upwardly extending driving arm aligned with the standard and the stake and provided with an enlarged driving head adapted to receive a driving impact, a second like unit section associated with the first unit section, a dowel carried by the body of one section and extended therefrom through the body of the other section, and a frangible connection between the two sections at a point relatively close to the dowel.

JAMES H. JACOBSON.
